ANTISTICK ELECTROMAGNET WITH
ARMATURES

Oliver W. Hopkinson, Jr., Brackenridge, Pa.

Application August 11, 1948, Serial No. 43,744

5 Claims. (Cl. 175—337)

1

This invention relates to magnetic contactors, such as electric circuit makers and breakers.

It is among the objects of this invention to provide a magnetic contactor in which sticking electric contacts cannot prevent the contactor from opening.

In accordance with this invention an electromagnet is mounted adjacent the free end of a pivotally mounted arm. When the magnet is energized, the arm is attracted toward it and closes electric contacts in an electric circuit that is controlled by the movements of the arm. When the magnet is deenergized, the arm is supposed to swing away from it so that the contacts will separate. To insure that this will happen in spite of a not infrequent tendency of the contacts to stick together, the core of the electromagnet is provided with an axial passage through it in which a core-like striker is slidably mounted. When the coil of the magnet is energized, the striker is drawn back into the core passage to space its front end from the arm that engages the front end of the core. A driving member is disposed at the rear end of the striker for driving it forward when the coil is deenergized. When this happens the striker hits the arm and knocks it away from the magnet, even though the contacts tend to stick together. The driving member may take various forms. It may be in the form of a solenoid core which is drawn up in a vertical passage in a solenoid coil above the rear end of the striker projecting from the electromagnet. In such a case, when both coils are deenergized the vertical core will drop down and push the striker forward. Or, the driving member may be a coil spring compressed behind the striker for driving it forward when the electromagnet is deenergized.

The invention is illustrated in the accompanying drawings in which Fig. 1 is a side view of my magnetic contactor closed; Fig. 2 is a vertical section taken on the line II—II of Fig. 1; Fig. 3 is a view similar to Fig. 1, but with the contactor open; and Fig. 4 is a fragmentary side view of a modification with the contactor closed.

Referring to Figs. 1 and 2 of the drawings, a platform 1 is provided with a central depending lug 2 having a pivot pin 3 projecting from its opposite sides into suitable supports 4. The platform carries electric contacts 6 that engage fixed contacts 7 supported at one side of the platform in any suitable manner. These contacts are connected in the electric circuit or circuits to be controlled. Rigidly mounted on the center of the platform is the lower end of an upright arm

2

8. The upper end of the arm has above the platform a side contact face 9 that is shown engaging the front end of the upper leg of a stationary U-shape core 10 disposed above the platform. Wound around this upper leg of the core is an electric coil 11 to form an electromagnet. Consequently, when this coil is energized, the contact face of the arm is attracted to the front end of the core at the center of the coil, whereby the arm 10 swings the contacts on the platform into engagement with the stationary contacts. When the coil is deenergized, the off-center weight of the arm is supposed to cause it to swing away from the magnet in order to separate the contacts, as shown in Fig. 3. However, occasionally the contacts weld themselves together sufficiently to prevent the arm from separating them, and thus maintain the circuit closed.

It is a feature of this invention that means is provided for positively swinging the arm away from the coil when it is deenergized, even though the contacts otherwise would have stuck together. Accordingly, the upper leg of the core is provided with an axial passage 14 through it in which a striker is slidably mounted. This striker has the same cross sectional shape as the passage, preferably square. The striker has a solid metal body 15 which is somewhat shorter than the coil so that when the body is centered therein the front end of the striker will be spaced from the front face of the core. Secured to opposite sides of the body of the striker are a pair of strips or legs 16 that extend out of the rear end of the core passage. These legs may be metal or any other suitable material. The rear ends 17 of these legs are preferably inclined upward and forward.

Rigidly mounted above the projecting rear end of the striker is a second coil 20 which has a vertical passage through it. Slidably mounted in this passage is a core-like driving member 21 that most suitably is rectangular in cross section. It is drawn up in the coil when the latter is energized. The lower front corner of the driving member is beveled off to form an inclined surface 22 having the same inclination as the rear end of the striker below it. The position of the driving member is such that when it moves downward the lower edge of its inclined surface 22 will overlap and engage the upper end of the inclined rear end 17 of the striker and then slide down that surface, which will push the striker forward in the core. To limit forward movement of the striker, its rear end may be provided with a downwardly projecting pin 23 that extends

through a horizontal slot 24 (Fig. 2) in a bracket 25 attached to the back of the core. The length of the slot controls the movement of the striker. The rear end of the bracket may be turned up for engagement with the back side of the dropping driving member 21 to prevent it from binding in coil 20.

In operation, the two coils generally are connected in the same circuit so that when the main coil 11 is deenergized, the second coil 20 will be deenergized at the same time. When this occurs, the driving member 21 is released and drops by gravity onto the inclined rear end 17 of the striker. The impact drives the striker forward in core 10 so that the front end of the striker is caused to strike the contact face 9 of the arm and knock it away from the core if sticking contacts have tended to hold it there. To secure the desired impact, the driving member may be provided with extra weight, such as by mounting a vertical pin 27 in its upper end and placing the desired member of perforated weights 28 on that pin. When the coils are energized again, the driving member 21 is drawn up in upper coil 20, and the striker body 15 is drawn back into the passage in the stationary core 10. At the same time, of course, the contact face 9 of the arm is drawn against the upper end of the core to close the contacts 6 and 7.

In the modification shown in Fig. 4, only a main coil 31 is used. In this case the driving member is in the form of a coil spring 32 which is compressed between the rear end of a short metal striker 33 and a plate 34 that closes the rear end of the passage 36 through the upper leg of the core 31. When the coil is energized, the striker is pulled back in the passage far enough to space its front end a short distance from the contact face of the pivotally-mounted arm 38. When the coil is deenergized, the magnetic force that held the striker back disappears, so the coil spring drives the striker forward against the arm to swing it away from the core and thereby separate the electric contacts 40 and 41. It will be noted that the striker moves a short distance before it strikes the arm, like a hammer, and that the striker and spring do not exert any pressure against the arm while it is engaging the core. This is because the spring is compressed by the striker which is withdrawn into the core by magnetic attraction.

According to the provisions of the patent statutes, I have explained the principle of my invention and have illustrated and described what I now consider to represent its best embodiment. However, I desire to have it understood that within the scope of the appended claims, the invention may be practiced otherwise than as specifically illustrated and described.

I claim:

1. A magnetic contactor comprising a pivotally mounted arm having a free end made of magnetic material, an electric coil adjacent the free end of the arm, a core of magnetic material in the coil for attracting the free end of the arm when the coil is energized, the core being provided with an axial passage therethrough, a striker slidably mounted in said passage with its front end spaced from said arm and its rear end projecting from the core when the coil is energized, at least a portion of the striker in said passage being made of magnetic material, a second coil mounted above the rear end of the striker and provided with a vertical passage, and a driving member of magnetic material drawn up in said vertical passage,

when the second coil is energized, the lower end of said member and the rear end of the striker being adjacent each other, and at least one of said adjacent ends having an inclined surface for engaging the other so that when the coils are deenergized the impact of the falling driving member against the rear end of the striker will drive the striker forward to knock said arm away from said core.

2. A magnetic contactor comprising a pivotally mounted arm having a free end made of magnetic material, an electric coil adjacent the free end of the arm, a core of magnetic material in the coil for attracting the free end of the arm when the coil is energized, the core being provided with an axial passage therethrough, a metal striker slidably mounted in said passage with its front end withdrawn therein and its rear end projecting therefrom when the coil is energized, at least a portion of the striker in said passage being made of magnetic material, a second coil mounted above the rear end of the striker and provided with a vertical passage, and a driving member of magnetic material drawn up in said vertical passage when the second coil is energized, the lower end of said member and the rear end of the striker being adjacent each other, and said adjacent ends having upwardly and forwardly inclined surfaces adapted to slide against each other when the coils are deenergized and the driving member drops, whereby the driving member will drive the striker forward to knock said arm away from said core.

3. A magnetic contactor comprising a pivotally mounted arm having a free end made of magnetic material, an electric coil adjacent the free end of the arm, a core of magnetic material in the coil for attracting the free end of the arm when the coil is energized, the core being provided with an axial passage therethrough, a striker slidably mounted in said passage with its front end spaced from said arm and its rear end projecting from the core when the coil is energized, the striker having a solid metal body of magnetic material in the core and horizontally spaced legs projecting from the rear end of said passage, a second coil mounted above the rear end of the striker and provided with a vertical passage, and a driving member of magnetic material drawn up in said vertical passage when the second coil is energized, the lower end of said member and the rear end of the striker being adjacent each other, and at least one of said adjacent ends having an inclined surface for engaging the other so that when the coils are deenergized the impact of the falling driving member against the rear end of the striker will drive the striker forward to knock said arm away from said core.

4. A magnetic contactor comprising a pivotally mounted arm having a free end made of magnetic material, an electric coil adjacent the free end of the arm, a core of magnetic material in the coil for attracting the free end of the arm when the coil is energized, the core being provided with an axial passage therethrough, a striker slidably mounted in said passage with its front end spaced from said arm and its rear end projecting from the core when the coil is energized, at least a portion of the striker in said passage being made of magnetic material, a bracket projecting from the back of the core and provided with a horizontal slot in line with said passage, a pin projecting from the rear end of the striker into said slot for limiting forward movement of the striker, a second coil mounted above the rear end of the

striker and provided with a vertical passage, and a driving member of magnetic material drawn up in said vertical passage when the second coil is energized, the lower end of said member and the rear end of the striker being adjacent each other, and at least one of said adjacent ends having an inclined surface for engaging the other so that when the coils are deenergized the impact of the falling driving member against the rear end of the striker will drive the striker forward to knock said arm away from said core.

5. A magnetic contactor comprising a pivotally mounted arm having a free end made of magnetic material, an electric coil adjacent the free end of the arm, a core of magnetic material in the coil for attracting the free end of the arm when the coil is energized, the core being provided with an axial passage therethrough, a striker slidably mounted in said passage with its front end spaced from said arm and its rear end projecting from the core when the coil is energized, at least a portion of the striker in said passage being made of magnetic material, a second coil mounted above the rear end of the striker and provided with a vertical passage, a driving mem-

ber of magnetic material drawn up in said vertical passage when the second coil is energized, adjustable weights mounted on top of the driving member, the lower end of said member and the rear end of the striker being adjacent each other, and at least one of said adjacent ends having an inclined surface for engaging the other so that when the coils are deenergized the impact of the falling driving member against the rear end of the striker will drive the striker forward to knock said arm away from said core.
